Primary Examiner — T. Chase Nelson*Assistant Examiner* — Jonathan J. Han(74) *Attorney, Agent, or Firm* — Merchant & Gould, P.C.(57) **CLAIM**

The ornamental design for a firearm handguard, as shown and described.

DESCRIPTION

FIG. 1 is a top, front, left side perspective view of a firearm handguard according to the present disclosure;

FIG. 2 is a right side view of the firearm handguard of FIG. 1;

FIG. 3 is a left side view of the firearm handguard of FIG. 1;

FIG. 4 is a front view of the firearm handguard of FIG. 1;

FIG. 5 is a rear view of the firearm handguard of FIG. 1;

FIG. 6 is a top view of the firearm handguard of FIG. 1;

FIG. 7 is a bottom view of the firearm handguard of FIG. 1; and,

FIG. 8 is a bottom, front, right side perspective view of the firearm handguard of FIG. 1.

The broken lines in the figures are used to illustrate unclaimed portions of the firearm handguard and form no part of the claimed design.

1 Claim, 5 Drawing Sheets(56)
